UNITED STATES PATENT OFFICE

HENRY WALDMAN, OF NEW YORK, N. Y.

PROTECTIVE BOOK COVER

Application filed May 2, 1932. Serial No. 608,721.

This invention relates to improvements in book covers and has particular reference to supplemental covers used for the protection of the permanent bindings of books.

Books, while on the book seller's shelf, usually, have a temporary protective cover, but such covers are not durable when constantly handled, nor, are they easily kept in place while in use. In order to provide an efficient protective cover, for the permanent binding, as the necessity demands I have provided an inexpensive substitute therefor.

The object of this invention is to provide a protective cover for books which can be easily applied and easily removed without injury to the said cover.

Another object of my present invention is to provide an adjustable cover which can be fitted to the various sizes of books.

The protective cover may be made of leather, oiled cloth, fabric, or other suitable material. A plurality of flexible metal strips are secured to the said cover adjacent the top and bottom edges so as to bind the cover firmly to the permanent binding of the book. The cover may be further provided with cut-out portions, said openings being covered with transparent material so that the title of the book remains visible.

With these and other objects in view my invention resides in the combination and arrangement of the various parts described in the following specification and later claimed.

It is to be understood that the invention is not limited to the exact details herein disclosed, still for the purpose of showing a preferred embodiment thereof reference is had to the accompanying drawing in which like numerals designate like parts in the separate views and in which

Figure 1 is a perspective view of a book with the protective cover partly in place.

Figure 2 is a plan view of the cover with parts broken away.

Figure 3 is a fragmentary view showing the cover adjusted to a smaller size book.

Figure 4 is a fragmentary view of a modified form of the cover.

Figure 5 is a view of the modified form folded at the corner.

Referring to the drawing in detail, 33 denotes a book having the usual permanent cover board portions 34, and 35. The protective cover 36 is provided with the metal strip 37 secured within the fold 38 along the top edge 39 of said cover.

The bottom edge 40, of the cover 36, is provided with the metal strip 41, secured within the fold 45. The edges 46 and 47 of the folds or hems 45 and 38 are stitched down, in this instance, as shown at 48 and 49, but may be otherwise fixed.

The metal strips 37 and 41 extend beyond the side edges 50 and 51 as shown. The extended ends of the metal strips 37 and 41 are covered with cloth or other soft material so as not to injure the book when clamped over the edges as shown at 57.

The cover 36 has a portion cut away along the line 55, said cut-away portion is covered with a transparent material 56 through which the name of the book can be seen.

It may sometimes happen that the book is somewhat smaller than the protective cover, in such a case, the bottom portion of the covering is rolled under or folded upon itself a plurality of times and adjusted to fit the book as shown in Figure 3.

In Figures 4 and 5 I have shown a modified form of cover 60 having the central portion 61 cut at 62 and 63 and folded down as at 64. The metal strips 65 and 66 extend from the outer edges of the cover to the points 67 and 68. The metal strips 65 and 66 are secured in position with strips of adhesive tape 69, or other suitable means. The upstanding portions 70 and 71 are folded down as shown at 72, in Figure 5, said fold being brought over the permanent book cover, and the outer edge of the protective cover is folded inwardly as shown at 73, Figure 5, which completes the operation.

To apply the protective cover 36, the book is placed over the inner surface of the cover and the sides 50 and 51 folded inwardly over the permanent cover, the metal strips being crimped sharply over the edges of said permanent cover. The extended ends of the metal strips crimped over the top and bottom edges of the book cover, as shown at 57, Fig-

ure 1, which hold the protective cover firmly in place.

Having thus described my invention and the manner in which the same may be applied, what I claim as new and desire to secure by Letters Patent, is:

1. A book cover of rectangular shape for the back and sides of a book comprising a sheet of protective material, and narrow bands of flexible metal, the top and bottom edges of said material being folded a plurality of times upon itself to form a hem, said flexible bands being disposed within said hem the book cover with its metal bands being equal in height to that of the book to be covered and longer than the combined cover boards and back of the book whereby when applied the side edges of the cover engage the inner surfaces of the cover boards.
- 15 2. A hook cover of substantially rectangular shape equal to the height of the book to be covered and longer than the combined back and cover boards of the book, and metal strips secured to the top and bottom edges of the cover and extending beyond the side edges of the cover board whereby when the cover is applied said strips may be bent around the side edges of the cover boards and into engagement with the inner surfaces of the cover boards at the top and bottom edges thereof to grip the same.
- 25 3. A protective book cover of pliable material and bands of flexible metal secured adjacent the top and bottom edges of said book cover and being of a length greater than the width of said cover and capable of being bent into clamps for securing said cover to said book.
- 35 4. A book cover of substantially rectangular shape and slightly larger than the back and sides of the book to be covered, and metal strips secured to the top and bottom edges of the cover and extending beyond the side edges of the cover whereby when the cover is applied said strips may be bent around the sides of the book and into engagement with the top and bottom edges of the sides of the book, each of said metal strips being of one piece and extending entirely across the sides of the book and around the back.
- 45
- 50
- 55

In testimony whereof I have signed my name to this specification.

HENRY WALDMAN.
